(57) **CLAIM**

The ornamental design for a female 4 prong receptacle, as shown and described.

DESCRIPTION

FIG. 1 is a top, front and right side perspective view of a female 4 prong receptacle, showing our new design; FIG. 2 is a front elevation view thereof, on a larger scale; FIG. 3 is a left side elevation view thereof, on a larger scale. The right side elevation view is a mirror image thereto; FIG. 4 is a top plan view thereof; FIG. 5 is a bottom plan view thereof; and, FIG. 6 is a back elevation view thereof, on a larger scale.
